Spinkerton

ATTORNEY

UNITED STATES PATENT OFFICE.

CHARLES ALBERT EYMAN, OF NEW YORK, N. Y.

VANITY CASE.

Application filed March 14, 1927. Serial No. 175,024.

This invention relates to vanity cases.

In the more expensive type of vanity cases having an ornamental finish or the like high grade ornamentation, it is desirable to provide a construction wherein the individual parts of the vanity case may be replaced by others of similar construction and interchangeable therewith and having different kinds of styles of ornamentation thereon.

10 In this way, by merely providing a stock of standard parts vanity cases having various designs or kinds of surface ornamentation may be assembled therefrom at a minimum expense.

15 It is one object of this invention to provide a vanity case of the character described which shall be made of individual parts that may be demountably secured together and readily assembled and disassembled so as to make available a large assortment and selection of vanity cases of the better grades or of the so-called "made to order" type having desirable combinations of colors or ornamentations and which may be assembled from individual 25 parts carried in stock.

Another object of the invention is to provide vanity cases having improved base structures, the parts thereof such as the casing top or cover and bottom being individually 30 formed to facilitate applying surface decorations such as enamel and constructed to be readily assembled.

35 Still another object of the invention is to provide a vanity case of improved construction having a pivoted cover supported by a hinge which normally is concealed from view when the cover is closed.

Another object of the invention is to provide an improved vanity case of the character 40 described having a compartment wall for retaining loose powder in the casing against accidental spilling on opening the cover thereof and which carries a receptacle such as a rouge holder or photo locket, said wall and receptacle being adapted to swing out of the vanity case into a convenient position for using the cosmetics with a mirror supported on the cover of the vanity case.

50 Still another object of the invention is to provide a vanity case of improved construction comprising few and simple parts, which are readily assembled to form a neat appearing artistic structure, and practical and efficient to a high degree in use.

55 Other objects of this invention will in part

be obvious and in part hereinafter pointed out.

The invention accordingly consists in the features of construction, combinations of elements, and arrangement of parts which will 60 be exemplified in the construction hereinafter described, and of which the scope of application will be indicated in the following claims.

In the accompanying drawing, in which is shown one of the various possible illustrative 65 embodiments of this invention,

Fig. 1 is a top plan view of a vanity case embodying the invention showing the top cover in open position.

Fig. 2 is a front elevational view showing 70 the cover in open position and the partition lid swung out of the case.

Fig. 3 is a sectional view corresponding to a cut taken on line 3—3 in Fig. 1 but showing the partition lid swung in its open position.

Fig. 4 is a fragmentary cross-sectional view showing in detail the construction of the hinge and catch for the cover.

Figs. 5 and 6 are cross-sectional views taken on lines 5—5 and 6—6 in Fig. 4.

Fig. 7 is a fragmentary cross-sectional view showing the handle on the lid in depressed position.

Referring in detail to the drawing, 10 denotes a vanity case embodying the invention. Said case is seen to comprise a body or casing portion 11, a top or cover 12, and a bottom closure 13. Said cover 12 is pivotally fastened to the casing by a detachable hinge 15 which is normally concealed within the casing structure and the bottom closure is demountably secured in place to permit both the cover and bottom closure to be interchanged with others of identical shape and size, as will herein-after more fully appear. A catch 21 mounted 95 in the casing is provided and preferably positioned opposite the hinge 15 for retaining the cover in closed position.

The casing 11 may have any desired contour and comprises an outer base member 11^a and an inner wall ring 16. The base member 11^a and wall ring 16 are permanently secured together to form a tubular structure, said ring member being formed with a threaded portion 16^a for engaging with threads 13^c provided on an annular flange 13^d extending about the bottom closure 13. As shown in the drawing the ring member 16 and said closure 13 form a compartment C for holding a suitable cosmetic, such as loose powder 110

and a puff (not shown) in the well understood manner. The cover 12 carries concentrically on the inner side thereof a frame 17 for securing a mirror 18 therein, the latter being adapted to swing with the cover on the casing by means of the hinge 15.

Said hinge has its pivoted portion 15^a positioned within the tubular structure of the casing 11 and has one of the hinge members 10 15^b anchored to the interior side of the inner wall ring member 16 by screws 19, the other hinge member 15^c being formed with an arcuately shaped portion 15^d extending through a passage 16^b provided in the ring member 16. Said arcuate portion terminates in a cross-piece 15^e which is shaped to conform to and abut against the mirror frame 17 and is secured thereto by screws 20. Thus, the hinge is normally concealed from view 15 when the cover 12 is in its closed position, as is clearly shown in Fig. 4.

For retaining the cover 12 in closed position, the catch 21 is provided and preferably is positioned diametrically opposite the hinge 25. Said catch comprises a spring latch 21^a extending within the tubular structure of the casing and is secured to the ring wall member 16 by a screw 22. Said latch 21^a extends through an opening 16^c in the wall 30 member and terminates in a hook end 21^b which is adapted to engage with an eyelet 12^c extending from the cover 12. A push lever 21^d has an end thereof threaded into the latch 21^a as at 21^d and extends through 35 an opening 11^c in the casing, the exterior end of said lever being provided with a ball 21^e to serve as manipulating means for the catch 21.

In order to facilitate the releasing of the 40 cover 12 from the catch 21, a suitable spring 23 is provided to abut the hinge member 15^c so that the cover when in closed position is normally urged to swing open on releasing the catch, as is clear from Fig. 4. Said spring 45 may be firmly secured in position in any suitable manner as by securing one end thereof in the clip 24 formed on the base member 11^a within the tubular structure of the casing.

For retaining the loose cosmetic within the compartment C against spilling should the cover be accidentally opened and the casing turned upside down, and also to prevent the mirror from being coated by any of the cosmetic, a suitable partition wall 25 is provided. To give access to the compartment C, said wall is formed with a central opening 25^a having a ring flange 25^b which is fixedly secured to the wall ring 16. The opening 25^a is fitted with a lid 25^c which preferably carries on the underside thereof a receptacle 26 having a hinged closure 26^a for rouge or the like. The receptacle 26 may be made to extend through the lid 25^c or if desired 65 the top side of the lid may be utilized to

carry a hinged bezel 27 for holding a photograph or medallion which is exposed to view on opening the cover 12. (See Fig. 1.) The lid 25^c may be frictionally retained in the opening 25^a and for this purpose, the rim 70 of said opening may be stepped as at 25^d.

As seen from Fig. 3, said lid is secured to said ring flange 25^a by means of a double hinge 25^d so that it may be swung out of the vanity case into a convenient position for 75 applying the cosmetics from the compartment C and the receptacle 26 with the aid of the mirror 18.

To facilitate opening the lid, a suitable handle 28 is provided. Said handle is collapsible and comprises a knob 28^a formed with a shank portion 28^b which extends through the lid, said portion 28^b terminating in a pressure plate 28^c which coacts with a compression spring 28^d enclosed in a housing 28^e secured on the underside of the lid, as is clearly shown in Fig. 3. The knob 28^a of the handle 28 is normally depressed when the cover 12 is closed and serves to retain the lid tightly seated in closed position but when the cover is swung open, the knob is projected a substantial distance above the lid to facilitate grasping thereof for swinging the lid open.

The parts of the vanity case are preferably formed of metal having a suitable decorative finishing surface, and as here shown, the casing 11, cover 12 and bottom closure 13 are formed with metallic base members 11^a, 12^a and 13^a, coated with ornamental layers 11^b, 12^b and 13^b respectively. It will be noted that the outer structure forming the vanity case comprises three parts, the casing 11, the cover 12 and the bottom closure 13. These parts have their finished surfaces ornamented before the vanity case is assembled and where an ornamented enamel coating or any other applied decoration is provided, these parts may be exposed to the necessary firing process prior to assembling. The bottom closure 13 and cover 12 are demountable from the casing to permit interchanging thereof with similar covers and closure members which are differently ornamented so that a 105 relatively large assortment and selection of vanity cases is made available from stock parts, and a so-called "custom made" vanity case having a selected desired combination of colors and ornamentation may be readily produced.

The practical use of the vanity case is now apparent. After assembling the parts as shown in Fig. 4 pressure is applied to the ball end 21^e of the catch. This disengages the hook end 21^b from the eyelet 12^c and the spring 23 acting against the member 15^c of the hinge 15 swings the cover 12 open. It may then be opened wide to the position shown in Figs. 1 and 2. Releasing the cover permits the knob 28^a of the handle 28 to be projected 115 125 130

- above the lid 25° so that the latter may be swung open and positioned as shown in Fig. 3 to permit the convenient application of the cosmetics from the compartment C and receptacle 26 by the use of the mirror. To close the vanity case the lid 25° is shut enclosing the cosmetics in the compartment C and the cover 12 is swung down until the catch 21 is secured in closed position.
- 10 It will thus be seen that there is provided a device in which the several objects of this invention are achieved, and which is well adapted to meet the conditions of practical use.
- 15 As various possible embodiments might be made of the above invention, and as various changes might be made in the embodiment above set forth, it is to be understood that all matter herein set forth or shown in the 20 accompanying drawing is to be interpreted as illustrative and not in a limiting sense.
- Having thus described my invention, I claim as new and desire to secure by Letters Patent:
- 25 1. A vanity case of the character described comprising an annular-shaped tubular casing, a bottom closure forming a compartment in the casing, a hinge secured to an interior side of the tubular casing structure and 30 extending through said structure, and a cover forming a closure for the casing supported by said hinge to normally conceal the latter when in closed position.
2. A vanity case of the character described comprising an annular-shaped tubular casing, a bottom closure forming a compartment in the casing, a hinge secured to an interior side of the tubular casing structure and extending through said structure, a cover forming 35 a closure for the casing supported by said hinge to normally conceal the latter when in closed position, and a catch extending through the casing structure and engaging said cover for retaining it in closed position.
- 40 3. In a vanity case of the character described, a casing body comprising an outer base member, an inner wall ring secured to said member to form an annular-shaped tubular structure, and a bottom closure detachably secured to said wall ring to form a compartment within the casing.
- 45 4. In a vanity case of the character described, a casing body comprising an outer base member, an inner wall ring secured to said member to form an annular-shaped tubular structure, a bottom closure detachably secured to said wall ring to form a compartment within the casing, and a hinged cover for the compartment detachably secured to the casing body.
5. In a vanity case of the character described, a casing body comprising an outer base member, an inner wall ring secured to said member to form an annular-shaped tubular structure, a bottom closure detachably secured to said wall ring to form a compartment within the casing, a hinged cover for the compartment detachably secured to the casing, and a partition wall in said compartment having a lid adapted to retain a cosmetic in the compartment against accidental opening of the cover and overturning of the case.
6. In a vanity case of the character described, a casing body comprising an outer base member, an inner wall ring secured to said member to form an annular-shaped tubular structure, a bottom closure detachably secured to said wall ring to form a compartment within the casing body, a hinged cover for said compartment detachably secured to the casing, a partition wall in said compartment having a lid adapted to retain a cosmetic in the compartment against accidental opening of the cover and overturning of the case, a receptacle carried on the underside of said lid and a double hinge for said lid to permit swinging the latter out of the case to a convenient position for using cosmetics in said compartment and said receptacle.
7. In a vanity case of the character described, a casing formed with a compartment, a cover for said compartment movably supported on said casing, a partitioning lid supported to swing in and out of said compartment, and an extensible handle on said lid, said handle normally being depressed on closing said cover.
8. In a vanity case of the character described formed with a partition, a movable closure for said compartment, a partitioning lid in said compartment, a receptacle carried on the underside of said lid, and a double hinge for swinging said lid out of the case to a convenient position for using cosmetics in the compartment and said receptacle.
9. In a vanity case of the character described, a casing formed with a compartment, a movable closure for said compartment, a partitioning lid in the compartment, a holder carried on one side of the lid, a receptacle carried on the side of said lid opposite said holder, and a double hinge for swinging the lid out of the case to a convenient position for using cosmetics in said compartment and said receptacle.

In testimony whereof I affix my signature.

CHARLES ALBERT EYMAN.
